(57) **CLAIM**

We claim the ornamental design for a connector, as shown and described.

DESCRIPTION

FIG. 1 is a forward perspective view of a connector; FIG. 2 is a forward plan view of the connector shown in FIG. 1;

FIG. 3 is a rear plan view of the connector shown in FIG. 1; FIG. 4 is a left side view of the connector shown in FIG. 1; FIG. 5 is a right side view of the connector shown in FIG. 1;

FIG. 6 is a top plan view of the connector shown in FIG. 1; FIG. 7 is a bottom plan view of the connector shown in FIG. 1;

FIG. 8 is an exploded forward perspective view of the connector in FIG. 1; and

FIG. 9 is an exploded rear perspective view of the connector in FIG. 1;

FIG. 10 is a forward perspective view of another embodiment of the connector;

FIG. 11 is a forward plan view of the connector shown in FIG. 10;

FIG. 12 is a rear plan view of the connector shown in FIG. 10;

FIG. 13 is a left side view of the connector shown in FIG. 10;

FIG. 14 is a right side view of the connector shown in FIG. 10;

FIG. 15 is a top plan view of the connector shown in FIG. 10;

FIG. 16 is a bottom plan view of the connector shown in FIG. 10;

FIG. 17 is an exploded forward perspective view of the connector in FIG. 10; and,

FIG. 18 is an exploded rear perspective view of the connector in FIG. 10;

The broken lines shown represent unclaimed subject matter and form no part of the claimed design. The shade lines shown represent surface shading and not surface ornamentation, color, or material type. The dot-dashed boundary lines shown do not form part of the claimed design. The bounds of the claimed design are defined with dot-dashed boundary lines when the boundary does not exist in reality in the article embodying the design. The illustrated designs extend to the boundary but do not include the boundary.
